UNITED STATES PATENT OFFICE

2,167,672

SUB-MACHINE GUN

Louis Nolan Nomar, Charleston, W. Va.

Application July 23, 1937, Serial No. 155,337

14 Claims.

(Cl. 42—4)

This invention relates to a gun of the sub-machine type.

The invention aims to provide, in a manner as hereinafter set forth, a gun of the class referred to including means whereby automatic rapid firing is obtained.

The invention further aims to provide, in a manner as hereinafter set forth, a gun of the class referred to so constructed and arranged as 10 to provide for rapid automatic loading from the stock thereof.

The invention further aims to provide, in a manner as hereinafter set forth, a gun of the class referred to including means to prevent the 15 jamming thereof when operated.

The invention further aims to provide, in a manner as hereinafter set forth, a gun of the class referred to so constructed and arranged for firing cartridges at the rate of twenty-eight hundred 20 per minute.

A further object of the invention is to provide, in a manner as hereinafter set forth, a gun of the class referred to having the elements thereof so arranged for reducing frictional heat to a 25 minimum.

A further object of the invention is to provide, in a manner as hereinafter set forth, a gun of the class referred to which practically eliminates heat of convection and conduction and further 30 reduces heat radiation to a minimum due to the rapidity of firing.

A further object of the invention is to provide, in a manner as hereinafter set forth, a gun of the class referred to so constructed and arranged 35 whereby the barrel, breech-block carrier, and breech block move rearwardly in unison for a part of the impulse due to recoil when the explosion occurs and whereby the breech block moves rearwardly independently of the barrel and carrier 40 for the remaining part of the impulse against the action of a means which acts to normally propel the breech block forwardly and with said means becoming active on the discharge of the bullet.

A further object of the invention is to provide, in a manner as hereinafter set forth, a gun of the class referred to so constructed and arranged to provide for the barrel moving rearwardly on the instant of explosion and for automatically 50 moving the barrel to firing position on the instant of discharge.

The invention further aims to provide, in a manner as hereinafter set forth, a gun of the class referred to so constructed and arranged to 55 maintain the pressure produced at the instant of

explosion until the bullet has left the barrel whereby the penetrating effect or distance of and for the bullet are not reduced.

The invention further aims to provide, in a manner as hereinafter set forth, a gun of the class referred to which is comparatively simple in its construction and arrangement, strong, durable, compact, thoroughly efficient for the purpose intended thereby, readily assembled, automatic in its operation, provides for rapidity of 10 firing, readily repaired when occasion requires and comparatively inexpensive to manufacture.

To the above ends essentially and to others which may hereinafter appear, the invention consists of the novel construction, combination and arrangement of parts as will be more specifically referred to and as illustrated in the accompanying drawings wherein is shown an embodiment of the invention, but it is to be understood that changes, variations and modifications may be 20 resorted to which fall within the scope of the invention as claimed.

In the drawings:

Figure 1 is a side elevation of the gun,
Figure 2 is a fragmentary view of the gun in 25 rear elevation,

Figure 3 is a section on line 3—3, Figure 2,
Figure 4 is a fragmentary view of the gun in top plan,

Figure 5 is a section on line 5—5, Figure 2, 30
Figure 6 is a section on line 6—6, Figure 5,

Figure 7 is an inverted plan view of the breech,
Figure 8 is a section on the line 5—5, Figure 2 and showing the parts as they would appear when the gun is loaded, 35

Figure 9 is a section on line 9—9, Figure 8 showing the gun as it would appear when in position to be fired,

Figure 10 is a section on line 10—10, Figure 4,

Figure 11 is an inverted view in perspective of 40 the lock-block element,

Figure 12 is a section on line 12—12, Figure 11 when reversed with respect to the position of the lock-block element shown in Figure 11,

Figure 13 is a fragmentary view in perspective 45 of the sear latching member forming a part of the lock-block element,

Figure 14 is a perspective view of the trigger yoke,

Figure 15 is a perspective view of the finger 50 trigger,

Figure 16 is a perspective view of the shell ejector,

Figure 17 is a side elevation of the combined 55 firing pin and hammer element,

Figure 18 is an inverted plan view of the combined firing pin and hammer element.

Figure 19 is a side elevation of the supporting post for the actuating spring for the firing pin and hammer element.

Figure 20 is a top plan view of the spring supporting post.

Figure 21 is a side elevation of the combined controlling, locking and carrier element.

Figure 22 is an elevation of the element shown in Figure 21.

Figure 23 is a section on line 23—23, Figure 22.

Figure 24 is a top plan view of the element shown in Figure 21.

Figure 25 is a side elevation of the latching member for and carried by the element shown in Figure 21.

Figure 26 is a top plan view of the member shown in Figure 25.

Figures 27, 28 and 29 are respectively a front, a side and a rear elevation of the sear releasing element.

Figure 30 is a section on line 30—30, Figure 28.

Figures 31, 32 and 33 are respectively a side elevation, a rear elevation and a front elevation of the member for locking the element shown in Figure 21 to the gun stock.

Figure 34 is a section on line 34—34, Figure 3.

Figure 35 is a section on line 35—35, Figure 1.

Figure 36 is a top plan view of the head of the gun stock.

Figure 37 is a vertical lengthwise section on line 37—37, Figure 36.

Figure 38 is a transverse section on line 38—38, Figure 36.

Figure 39 is a transverse section on line 39—39, Figure 36.

Figure 40 is a transverse section on line 40—40, Figure 36, and

Figure 41 is a section on line 41—41, Figure 3.

The gun includes a hollow carrier 1 (Figure 4) which may be termed a housing, frame or body part. The carrier 1 is an integral casting having an open rear end which is closed by a means to be referred to. The carrier 1 is substantially rectangular in plan and includes a top 2 formed lengthwise and centrally thereof and intermediate its ends with a rectangular opening 3. The top 2 is also formed with a central opening 5 at its rear end, a rear arch-shaped portion 6 which constitutes the forward end wall of opening 5 and the rear end wall of opening 3. The top 2 also includes a front arch-shaped portion 7 which forms the forward end wall of opening 3. The portions 6, 7 also constitute coupling pieces for a purpose to be referred to. The bottom of carrier 1 is indicated at 8 (Figure 7) and it is formed centrally thereof with an opening 9 which extends from a point rearwardly of its front to its rear end. The forward wall of opening 9, indicated at 9a, has a curved portion 9b. The front end of carrier 1 (Figure 5) is in the form of a wall 10 integral with the portion 7. The wall 10 is formed centrally thereof with an opening 11 and a pair of openings 12, 13 located adjacent the sides of and of materially less diameter than that of opening 11. The wall 6 and portion 7 (Figures 4, 5 and 7) has formed integral therewith a forwardly disposed extension 14 of semi-oval contour in vertical section and of less width than that of carrier 1. The extension 14 is provided from end to end with an opening 15 having its wall forming a flush continuation of the wall of opening 11. The major portion of the length 75 of the opening 15 is threaded as at 16.

The carrier 1 includes a pair of spaced parallel oppositely disposed internal side parts 17, 18 (Figure 10) constituting combined guides and couplers for a breech block to be referred to. The portions 6, 7 couple parts 17, 18 together 5 at their tops. The parts 17, 18 are integral with wall 10. The parts 17, 18 extend from the inner face of wall 10 to a point in proximity to the open rear end of the carrier. The inner faces 18a of the parts 17, 18 form flush continuations 10 of the side walls of opening 9. The parts 17, 18 are of like form and their rear ends constitute shoulders. The parts 17, 18 are formed with cylindrical openings 19, 20 respectively and with squared passages 21, 22 respectively. The openings 19, 20 and passages 21, 22 extend from the forward to the rear ends of the parts 17, 18. The passages 21, 22 open at the inner faces 18a of the parts 17, 18 and communicate with the openings 19, 20 at the inner sides of these latter (Figure 20 10). The openings 12, 13 communicate with the forward ends of the openings 19, 20 respectively. The forward ends of the passages 21, 22 are closed by the wall 10. The bottom 8 (Figures 7 and 10) is provided lengthwise thereof with 25 oppositely disposed depending angle-shaped flanges 23, 24 having the inner faces of their vertical legs flush with the walls of the opening 9. The flanges 23, 24 extend from the forward to the rear end of bottom 8. The lower face of the 30 extension 14 forms a continuation of bottom 8 and the sides of the extension 14 are provided from end to end thereof with outwardly opening channels 25, 26 which form flush continuations 35 of the channels 23a, 24a. The purpose of the channels on bottom 8 and extension 14 will be hereinafter set forth. The bottom of extension 14 has a boss 26a (Figures 3 and 9) which carries a depending locking pin 27 for a purpose to be referred to. That portion of pin 27 below boss 26a 40 is formed with superposed spaced flanges 27a, 27b.

Arranged within the openings 19, 20 are a pair of shiftable combined guide and supporting members 28, 29 respectively having forward tubular portions 30 open at their front ends and rear solid portions 31 formed with reduced terminal parts 32. The members 28, 29 normally extend from a point adjacent the inner face of wall 10 to the rear end of carrier 1. The axes of the forward open ends of members 28, 29 align with 50 the axes of the openings 12, 13 respectively. The tubular portions 30 of the members 28, 29 are formed lengthwise of the tops and bottoms with diametrically opposed slots 33.

The rear end of carrier 1 is closed by a slideable 55 rear bridge element 34 which is inserted in the carrier and abuts against the shoulders provided by the rear ends of parts 17, 18. The element 34 is formed with a pair of aligned openings 35 for receiving the reduced/terminal parts 32 of the portions 31 of members 28, 29. The element 34 is formed with an axial opening 36, and an internally threaded collar 37 forming an outward continuation of the wall of opening 36. The outer face of element 34 at each side of collar 37 65 is recessed as at 38. The intermediate part 39 of element 34 is formed with a depending angle-shaped lug 40 which aligns with opening 36 and includes a forwardly extending transversely apertured horizontal leg 51 (Figure 3). The element 34 is anchored to the terminal parts 32 of the members 28, 29 by pins or studs indicated at 42. Extending into the recess 38 and abutting part 39 is an annular knob 43 which surrounds collar 37 and is detachably anchored to the inter- 75

mediate part 39 by a headed screw 44 engaging with the threads of collar 37. The inner face of knob 43 has an annular shoulder 45 aligning with the outer end edges of collar 37. When the screw 44 is in securing position the head 45 thereof abuts the outer end edge of collar 37 and shoulder 45 (Figure 5). The members 28, 29 and element 34 form what may be termed a combined breech block guide and carrier having associated therewith controlling springs to be presently referred to.

The barrel of the gun is indicated at 46 and which is rifled internally from its outer to a point removed from its inner end, as indicated at 47 (Figures 3 and 9). The barrel 46 includes an outer stretch 48, an intermediate stretch 49 and an inner stretch 50. The stretch 48 is of greater outer diameter than the other stretches and provided with spaced laterally disposed annular radiating fins 51. The stretch 49 at its inner end is formed with an annular peripheral shoulder 52. The stretch 50 for a portion of the length of its outer periphery is threaded, as at 53. The stretch 50 is formed of two different inner diameters. The portion 54 of smallest inner diameter of stretch 50 corresponds to the inner diameter of stretch 49, and is of less length than and arranged forwardly of the portion 55 of largest inner diameter of stretch 50. The junction of the portions 54, 55 provides the stretch 50 with an internal annular shoulder 56. The stretch 50 is of a length to correspond to the combined length of the walls of and is positioned in the openings 11, 15 (Figure 5). The threads 53 of stretch 50 coact with the threads 16 of extension 14 for securing the barrel 46 with the front of carrier 1. When barrel 46 is secured with carrier 1, the shoulder 52 abuts against the front of extension 14 (Figures 3, 8 and 9) and the inner end of stretch 50 is flush with the inner end of the beveled portion 57 (Figure 9) formed at the inner end of the wall of the opening 11. The stretch 50 is locked to extension 14 by the pin 27 (Figure 3).

The gun includes a spring controlled manually slidable mechanism 58 which coacts with other parts of the gun when the latter is not active to provide for initially loading the gun, after which the loading is had automatically. The mechanism 58 is slidably mounted on a combined supporting and suspension structure 59 therefor which is coupled at one end with the barrel 46 and at its other end is supported from the stock structure 60 of the gun.

The mechanism 58 includes a hand grip 61 disposed in lengthwise relation to the bottom of barrel 46 and has secured to the rear end an upstanding V-shaped plate 62 having its sides 63, 64 disposed at, spaced from and extending above the sides of the barrel 46. Fixed to the upper ends of the sides 63, 64 of the plate 62 are rearwardly extending parallel loading rods 65, 66 respectively which extend through the openings 12, 13 in wall 10 and into the tubular portions 30 of the members 28, 29 respectively. The rods 65, 66 coact with parts, to be referred to, of the gun for the purpose of initially loading the latter. The hand grip 61 is formed respectively with a groove lengthwise throughout its upper face, as at 67 (Figures 34 and 41), below and spaced from groove 67 with an opening 68 extending from one end to the other thereof and through plate 62, and between its vertical median and its rear end with a cutout 68a (Figure 41) for establishing communication between groove 67

and opening 68, as well as to provide a clearance for a coupler to be referred to.

The structure 59 (Figure 3) includes a T-shaped coupler 69 which extends through cutout 68a into opening 68 and is integral with and depends from the bottom of the stretch 49 of barrel 46. The stem 70 of coupler 69 is formed with an opening 71. Positioned in the opening 68 and of greater length than that of hand grip 61 is a tubular member 72 having a slot 73 in its top adjacent its forward end for the passage of coupler 69 and a pair of aligned slots 74 in and lengthwise of its sides, for a purpose to be referred to. The member 72 is formed of a forward stretch 75 and a rear stretch 76. The stretch 75 is of greater inner diameter and of greater length than stretch 76. The forward end of the latter provides an internal annular shoulder 77 within the member 72. The slot 73 is disposed longitudinally of stretch 75. The slots 74 are formed in stretch 76. The rear end of stretch 76 has its top reduced to form a shoulder 78 and its top is also cut out, as at 79 to provide a clearance for a purpose to be referred to. Slidably mounted in stretch 75 is a cup-shaped plunger 80 open at its rear end. Arranged within plunger 80 and extending from the open end of the latter to the shoulder 77 is a controlling spring 81 for the plunger. Slidably mounted in the opening 71, formed in the stem 70 of coupler 69, is a piston 30 rod 82 provided at its rear end with a piston head 83. The rear end of member 72 is closed by a flanged cap piece 84. A pin or stud indicated at 85 is employed for anchoring member 72, piston rod 82 and cap piece 84 together rearwardly of stem 70 of the coupler 69. Arranged in the member 72, surrounding rod 82 and interposed between stem 70 and piston head 83 is a cushioning spring 86. The rod 82, head 83, spring 86 and stem 70 coact to provide a shock-absorbing means 40 for the return movement of the hand grip 61. The rear end of the stretch 76 of the member 72 is mounted in a socket 87 formed in the stock structure 60. The shoulder 78 abuts the forward end of boss 26 and the cutout 79 forms a clearance for the lock-pin 27 and permits of the flange 27b of the latter being arranged in the rear end of member 72.

The mechanism 58 is slidably connected to and about the member 72 of structure 59 by a sleeve 88 (Figure 34) which extends through member 72 and is slidably arranged in the slots 74. The sleeve 88 is carried by a bolt 89. The sleeve 88 is arranged between the forward end of plunger 80 and piston head 83. The hand grip 61 is formed transversely thereof with a pair of inner endwise aligned oppositely extending openings 90, 91 which communicate at their inner ends with the opening 68. The bolt 89 is positioned in and spaced from the wall of the openings 90, 91 as well as extending through member 72. Fixed in the outer portion of the opening 91 is a spacing ferrule 92 for the head of the bolt 89. The head of the latter is countersunk in the ferrule 92. The outer end of opening 90 has arranged therein a combined spacing and retaining nut 93 for and which has threaded engagement with bolt 89.

The gun includes a horizontally disposed breech block element 94 (Figures 3, 5, 8 and 9) slidably mounted in and of less length than carrier 1. The element 94 consists of an integral casting or body part 95 provided at the forward ends of its sides with oppositely extending laterally disposed arms 96 (Figures 5 and 10) formed respectively

with necks 97 which extend through and are slidably mounted in the passages 21, 22 and with annular outer or head parts 98 which extend into the openings 19, 20 and encompass and are slidably mounted on the members 28, 29 (Figure 5). That body part 95, other than the arms 96 is arranged between the side parts 17, 18 of the carrier 1. The annular outer parts 98 have fixed thereto, on their vertical diametric centers, combined abutment and coupling pins 99 which pass through the slots 33 of the tubular portions of members 28, 29. The pins 99 provide for the slidably connecting of the element 94 to the member 28, 29, as well as constitute abutments 15 for the rear ends of the rods 65, 66 when they are shifted rearwardly to move element 94 in a like direction. The pins 99 also coact with the forward and rear walls of the slots 33 to constitute stops for the element 94.

20 The body part 95 of element 94 is formed with a chamber 100 in which is slidably mounted a combined spring and inertia actuated cartridge firing element 101 to be referred to. The chamber 100 is open at its rear. The bottom 102 (Figure 9) of the chamber 100 is formed with a centrally disposed slot 103 lengthwise thereof. The slot 103 is of less length than and opens at the rear end of bottom 102. The forward portion of the top 104 of body part 95 has formed in its upper face and at its lengthwise center a groove 105 (Figure 9) and communicating with the latter and chamber 100 is an opening 106. The latter is arranged intermediate the ends of the groove 105. The groove 105 and opening 106 are 30 for the reception of a shell extractor element 107 to be referred to. The groove 105 opens at the forward end of body part 95. The latter has its top 104 formed with a pocket 108 for a purpose referred to. The pocket 108 opens into the rear end of groove 105. The front 109 of body part 95 forms the forward wall of chamber 100 and is provided with an axial opening 111 for a purpose to be referred to. The opening 111 flares from its forward to its rear end.

45 The element 101 (Figures 3, 5, 8, 17 and 18) includes a hammer 112 formed of an intermediate solid portion 113 of circular cross section and uniform diameter which merges at its forward end into a solid tapered forwardly directed portion and at its rear end into the forward end of a tubular rear portion 114 open at its rear end. The portion 114, in cross section is of a contour greater than a half circle and less than a complete circle and having the circular portion of its outer periphery throughout upon a radius corresponding to that of the periphery of the part 113. The rear part of the lower face of portion 114 is lengthwise beveled as at 114a to form a flat inclined surface terminating at the rear end of portion 114. The bevel 114a extends upwardly from its forward end to the rear end of portion 114. There is integral with the rear end of the said inclined surface a depending keeper 115 having its rear face flush with the rear surface 60 of the portion 114. The keeper 115 is disposed centrally with respect to the rear end of the said inclined surface and confined within the perimeter of the portions 113, 114. The keeper 115 which associates with a sear or nose carried by 65 a hammer latching member 116 to be referred to for latching the element 101 in its initial position as shown in Figure 9. Arranged within the part 114 and extending rearwardly from the hammer 112 is the compression recoil and actuating 70 spring 117 for initially operating element 101.

The forward end of hammer 112, axially thereof is provided with a firing pin 118 of the same contour as and for passage through opening 111 in the front 109 of the breech block. Surrounding the pin 118 and interposed between the inner face 5 of the front 109 of element 94 and the forward end of hammer 112 is a compression spring 119.

Fixedly suspended at its upper end from the rear of element 94 is a seat element 120 for the rear terminal portion of the spring 117. The element 120 includes a post 121 formed above its lower end with a forwardly extending tapered rest 122. The rear side of post 120 is beveled forwardly from its transverse median to its lower end as at 123 to provide a clearance for a purpose 15 to be referred to. The post 121 near its upper end has an opening 124. The post 121 extends into a square pocket 125 (Figure 3) formed in the upper portion of the rear end of body part 95 of element 94 (Figure 3). The post 121 is fixedly 20 secured by a stud 126 (Figure 3) which extends through opening 124 and is anchored in body part 95. The element 120 is arranged in the open rear end of element 94. The tapered rest 122 extends into the rear terminal portion of the 25 spring 117. The keeper 116 is arranged below the post 121.

The gun includes a lock-block element 127 (Figures 3, 7, 11, 12 and 13) arranged rearwardly of the element 94, positioned and slidably engaging in the side parts 17, 18 of carrier 1. The element 127 includes a horizontally disposed body part 128 having its upper face 129 inclining upwardly from its rear end 130 to its forward end 131. The lower face 132 of body part 128 is flat. 30 The forward end 131 of body part 128 is oppositely inclined. Formed integral with the rear end 130 of body part 128 is a pair of rearwardly extending parallel apertured arms 133 for positioning at the sides of the apertured horizontal 35 leg 41 of lug 40. The arms 133 are pivotally connected with the leg 41 by a pivot pin 134 (Figure 3). The forward portion of the body part 128 is bifurcated as at 135 to form a pair of spaced parallel arms 136. Arranged between and 40 extended from the forward ends of the arms 136 is the latching member 116 consisting of a substantially oblong shank 137 having its rear portion bifurcated as at 138 to form a pair of spaced parallel rear arms 139 provided with aligning 45 openings 140. The shank 137 has the forward end of its upper face formed with an integral sear or nose 141 spaced from its side edges 142 and flush with the forward end edge 143 of the shank. The sear or nose 141 is substantially of 50 triangular contour with its front edge 144 inclined inwardly from its bottom to its top. The arms 139 are mounted on a pivot bar 145 which is anchored in and disposed transversely of body part 127 near the lower face 132 of the latter. 55 The arms 136 having the lower portions of their inner side faces provided with flanges 146 (Figure 12) which act as stops to arrest the arms 139 shifting lengthwise of pivot bar 145. Mounted on the bar 145 between the arms 139 is a coiled 60 controlling spring 147 for the latching member 116. The spring 147 functions to normally hold the sear or nose 141 in the path of keeper 115. The end 148 of the spring 147 is extended and seats in a groove 149 (Figures 3 and 11) formed 65 in the lower face of the shank 137. The other end 150 of spring 147 is extended and seats in a groove 151 (Figures 3 and 11) formed in the lower face 132 of body part 127. The latter in 70 proximity to its rear end has its sides formed with 75

curved laterally disposed guides 152 (Figure 11) which are slidably disposed in curved guide channels 153 (Figure 5) formed in the inner face 18^a of the parts 17, 18.

5 Surrounding the members 28, 29 and interposed between the arms 96 of element 94 and the bridge element 34 are recoil compression and bridge-block element actuating springs 154.

The shell extractor element 107 (Figures 4, 9 10 and 16) is in the form of a lever 155 of greater length than that of the groove 105 in which it is positioned. The lower face of lever 155 between its transverse median and rear end is formed with a depending apertured lug 156 arranged in opening 106 and mounted on a pivot 157 anchored to body part 95 of element 94. Element 107 is bodily carried with element 94. The rear end portion 158 of lever 155 is of reduced thickness and bears on a controlling spring 159 which is mounted in pocket 108. The forward end of lever 155 has a depending nose or hook 160 for engagement with the flange 161 at the rear end of the shell 162 of the cartridge 163 when the latter is in the firing chamber 164, formed by the portion 55 of greatest inner diameter of the stretch 50 of barrel 46. The forward end of element 107 is oppositely beveled. The bevel part 57 of the wall of the opening 11 in the front of carrier 1 provides a clearance for the forward end of element 107 when the latter is shifted to shell engaging position.

The stock structure 60 is of the extension type and of angular contour. The structure 60 includes a hollow body part 165 and a head 166, the former merging at its forward end into the latter. The body part 165 may be of the form as shown by Letters Patent No. 2,066,361, granted to me January 5, 1937, or of the form as embodied in my co-pending application, Serial No. 112,160, filed November 21, 1936. Patent No. 2,114,311. The body part 165 provides an elongated cartridge magazine 167 opening into the head 166. A cartridge guide 167^a is arranged in the magazine 167. The body part 165 is formed of an inner section 168 of frame-like contour and a pair of side sectional cheeks 169. The structure 60 carries a driven cartridge feeding mechanism which will be of the same form as that disclosed by the patent aforesaid or as that embodied in my co-pending application referred to. The cartridge feeding mechanism is indicated at 170.

The head 166 (best shown in Figures 1 and 36 to 40) is integral with the upper portions of the front, rear and side edges of the section 168 of body part 165 and extends upwardly, forwardly and rearwardly with respect to the forward end of body part 165. The head 166 has its rearwardly extending portion of greater length than its forwardly extending portion. The head 166 includes a pair of oppositely disposed side portions 171, 172 of like form and each of which is formed of an upper horizontal part 173 provided on its inner face in proximity to its top, with an inwardly opening channel 173^a corresponding in length thereto. Arranged between and integral with the inner faces of the parts 173 are the lower horizontal parts 174 of the side portions 171, 172. The parts 174 depend from and are inset relative to the parts 173. Each of the parts 174 is formed of a forward stretch 175, an intermediate stretch 176 and a rear stretch 177. The outer side face of stretch 175 is inset with respect to the outer side faces of the stretches 176, 177. The stretch 175 is of less height than stretch 176. The stretch 177 is of less length than that of

either of the stretches 175, 176 and gradually decreases in height from stretch 176. The latter is incut at its bottom to form a pair of straight spaced parallel edge portions 178, 178^a and a pair of arcuate edge portions 179 arranged above 5 the edge portions 178, 178^a. The rear ends of the stretches 177 have aligned openings 180.

The rear ends of stretches 175 and the forward ends of the stretches 176 are integral with a bridge piece 181 having oppositely curved sides 10 182, 183. The inner sides of the stretches 175 are formed with ledges 183^a below the top of bridge piece 181 and which extend from the side 182 of the latter to the forward ends of stretches 175. These latter have their inner sides below the 15 ledges 183^a oppositely curved. The lower ends of the stretches 175 at their forward portions merge into each other and in connection with the curved portions of their inner sides form the socket 87 (Figure 3). Formed integral with the 20 forward ends of the stretches 175 at their bottoms is one end of a curved arm 184. The latter has its other end integral with the front edge of the inner section 168 of the body part 165 of the stock. The inner face of arm 184 is grooved as 25 at 184^a for a portion of its length. The upper end of the groove 169 opens into the space 184^b formed between the stretches 175. The arm 184 in connection with the stretches 175 constitutes a guard for a shiftable trigger element 185 which 30 will be presently referred to. The groove 169 and space 184^b form a clearance for element 185 when the latter is shifted to and held in active position by manually applied pressure from the finger of the gunman. The element 185 coacts 35 with parts, to be referred to, of the gun to provide for the initial firing and continuous automatic firing of the gun. The inner sides of stretches 176 are connected together by a lower bridge piece 186 which is integral therewith and 40 arranged below the bridge piece 181. The bridge piece 186 is formed with oppositely disposed curved sides and is of less width than that of the bridge piece 181. The rear side of bridge piece 186 is arranged rearwardly of the rear side 45 of bridge piece 181. The bridge pieces 181, 186 are so formed and coact to provide a passage 186^a therebetween. The bridge piece 186 at its lower end is flush with the lower edge parts of the side portions 171, 172 of head 166. The tops of the 50 stretches 175 provide spaced parallel abutments or ledges 187. The tops 188 of the stretches 176 are spaced apart and are of less width and of greater length than the tops of the stretches 175.

The upper surfaces of tops 188 of the stretches 55 176 are downwardly inclined at their rear terminal portions, as at 189. The rear terminal portions of the tops 188 of the stretches 176 are tapered as at 190. The rear side 191 of the section 168 of body part 165 extends above the 60 front side 191^a of section 168 to between and is integral with the inner faces of side portions 171, 172. The upper end portion of said rear side 191 of body part section 168 is laterally enlarged and spaced below the top of the head 166. The upper end of said rear side 191 of body part section 168 is aligned with the upper face of bridge 181. The rear face of the said rear side 191 of body part section 168, in the upper portion thereof, is formed with a concave groove, as at 192 and 65 70 said rear face is also formed adjacent its top with a groove 193 transversely of the wall of groove 192. The inner faces of the stretches 177 at their end terminal portions are formed with oppositely outwardly inclined beveled surfaces 194 length- 75

wise thereof which constitute clearances and have their tops flush with the bottom of the channels on the inner faces of the side portions 171, 172 of the head 166. The surfaces 194 gradually increase in height from their outer to their inner ends. Below the surfaces 194, the inner faces of the stretches 177 are formed with oppositely upstanding beveled shoulders 195 which merge at their upper ends into ledges 196 positioned at the bottoms of the surfaces 194. The ledges 196 incline upwardly from their inner to their outer ends. The outer ends of the surfaces 194 and the ledges 196 are flush with the rear ends of the stretches 177. The inner faces of the side portions 171, 172 of the head 166 are formed with lower inset parts 197 which extend from the lower bridge piece 186 to the bottoms of the shoulders 195. The top of the inset parts 197 are flush with the upper face of bridge piece 186 and with the upper end of the side 191 of the section 168 of body part 165.

The carrier 1 is connected to the head 166 by the interengagement of the flanges 23, 24 with the channels 173a (Figure 10).

25 The trigger element 185 (Figure 15) includes a forwardly curved upstanding finger engaging part 198 having a rectangular flat top 199 with which is formed integral the lower lengthwise edge of a vertical narrow rectangular stem 200 centrally thereof. The upper lengthwise edge of the stem 200 merges into the flat lower face of a cap piece 201 of a length and width to coat with the top 199 and stem 200 to provide the upper part of element 185 with a pair of oppositely disposed 30 grooves 202, 203. The cap piece 201 is of a segmental contour in transverse cross section. There is associated with and rearwardly shifted by the element 185 a pusher element 204 (Figure 14) for releasing the combined firing pin and hammer element 101 to initially start firing. The element 204 is maintained in its shifted position by a continuous application of manually applied pressure to element 185 to provide for the continuous automatic operation of the gun. The element 204 includes a semi-oval shaped one-piece body part 205 of frame-like form having a forward curved end 206, a pair of straight sides 207 and a rear end 208 flush with the bottom edges of and of materially less height than that of the sides 207. 35 The upper face of end 208, centrally thereof is formed with an upstanding semicircular lug 209 constituting a pusher for a purpose to be referred to. Formed integral with the forward face of end 206 of body part 205 is a forwardly extending 40 stem 210 having its forward portion bifurcated as at 211a to provide a pair of spaced parallel arms 212a. The arms 212a have rounded outer and flat inner sides. When elements 185 and 204 are 45 associated together, the arms of element 204 are arranged in the grooves 202, 203 of the element 185 and the stem 200 of element 185 abuts the base of the furcation in the stem 210 of element 204. The element 185 is disposed in the guard formed by the arm 184. The stem 210 of element 50 204 is slidably mounted in passage 186a. The body part 205 of element 204 is slidably mounted on the ledges 187.

The gun includes a normally stationary pivoted combined controlling, connecting and carrier element 211 (Figures 2, 21 to 24) which is arranged within the rear portion of the head 166 between the ledges 197. The element 211 normally inclines downwardly from rear to front and is pivotally supported at its rear end on a pivot means 75 212. The means extends through openings 213

in element 211, through the openings 180 of stretches 177 and is secured to these latter. The element 211 is of a length to extend from the side 191 of body part section 168 to the rear end of head 166. The element 211 includes a horizontally disposed lower part 214 having an upstanding portion 215 at the forward portion of its top. The front end 216 of part 214 is of convex curvature. The upper portion of said end 216 has a U-shaped recess 217. The end 216 below and in proximity to the bottom of the recess 217 is formed with a transverse groove 218. The top 219 of the portion 215 inclines slightly downwards from rear to front. The part 214 is formed with a pocket 220 forwardly of its vertical median which opens at the bottom of part 214. The latter is formed with an opening 221 lengthwise thereof which establishes communication between groove 218 and pocket 220. The part 214 is provided with a lengthwise bore 222 which leads from pocket 220 to the rear end of part 214. The bore 222 is of materially greater diameter than that of opening 221 and has the major part 223 of its forward end opening into pocket 220. The other part of the forward end of bore 222 is closed as at 25 224. The element 211 is formed with a socket 225 arranged within part 214 and the upstanding portion 215. The socket 225 opens at its forward end into the lower part of recess 217. Formed integral with the sides of the top of portion 215 30 are the rear portions of the lower lengthwise edges of a pair of forwardly extending spaced parallel arms 228 of like form and length. Secured with the inner faces of the arms 228, below the upper lengthwise edges and rearwardly of the 35 forward end edges of said arms, is an inverted U-shaped member 229 having its sides formed with rear extensions 230 to provide ledges below the top edges of arms 228. The top edges of the extensions 230 are flush with the upper face of 40 the top of member 229. The latter is disposed in forward relation with respect to the portion 215 and has the inner faces of the sides thereof form flush continuations of a part of the side walls of the recess 217. The member 229 is spaced from 45 the forward and rear ends of the arms 228. The extensions 230 have their rear ends flush with the rear ends of the arms 228. The forward end of the top 231 of member 229 has centrally thereof an upstanding lug 232 constituting a shell rejector. The bottom of part 214 rearwardly of the pocket 220 is grooved as at 233 for a purpose to be referred to. The forward portions of the lower ends of the arms 228 constitute cartridge deflectors for tilting the cartridge upwardly and 50 directing the cartridge forwardly when it is passing from the head 166 into the loading chamber to be referred to. The said forward portions of the arms 228 are positioned between and extend above the tops 188 of the stretches 176. The tops 60 188 of the stretches 176, the upper portion of side 191 of body part section 168, the upper and lower bridge pieces, and the stretches 176 coat to form a passage 234 for the travel of a cartridge from the magazine to the carrier 1 forwardly of the 65 breech block element 94 on loading. The said lower edges of the forward portions of the arms 228 are arranged in the top of the passage 234 in the path of the cartridge.

The gun includes a horizontally shiftable releasing element 235 (Figures 1, 9, 27 to 30) for the sear or nose on the latching member 116. The element 235 is of angle-shaped contour and includes a vertical leg 236 and a horizontal leg 237 extending rearwardly from the lower end 75

of the leg 236. The leg 237 is tubular, closed at its forward end and open at its rear end. The leg 236 is arranged in the member 229 and the recess 217. The leg 237 is positioned in the socket 225. 5 Arranged within and extending from the rear end of leg 237 to the base 238 of socket 225 is a coiled controlling spring 229^a for element 235 (Figures 3 and 9). The leg 236 is positioned in the path of the pusher lug 209 formed on the element 204. 10 The upper rear corner of the leg 236 is beveled for coacting with the bevelled front of the nose 141 of the sear or latching member 116. The leg 236 may or may not be provided with an inclined notch for the reception of a part of a safety mechanism not shown. The leg 238 is shown as provided with such notch which is indicated at 238^a. The sear or nose 141 on the latching member 116, when the latter is in its initial latching or locking engagement with the element 101, is arranged 15 in the rearward path of travel of the leg 236 of element 235 whereby leg 236 will engage sear 141 and shift it from a latching or locking position, thereby releasing element 101 to provide for the latter becoming active. The shifting of the sear or latching member 116 to released position is had against the action of the spring 147. The leg 236 is held in shifted position by the continuous application of manually applied pressure to the trigger element 185 to hold the 20 sear clear of element 101 whereby the gun will be automatically operated, as long as such pressure is applied to element 185, for the purpose of firing all of the cartridges fed from the magazine. 25 The gun includes a structure 239 for normally locking the element 211 stationary to the stock whereby such element will be held in its correlated position with respect to the parts of the gun with which it is associated. The front 216 of element 211 when the latter is in its stationary position is seated on the groove 192. The structure 239 (Figures 3, 31 to 33) includes a locking member 240 formed with a locking head 241 and a stem 242 grooved on each of the sides as at 30 243, 244, to provide a pair of abutments 245, 246. The grooves 243, 244 reduce the thickness of the intermediate part 247 of stem 242. The bottom edge 248 of part 247 inclines downwardly from front to rear. The locking head 241 in plan is substantially of semi-circular contour. The stem 242 is secured to and centrally of the flat edge 248^a of head 241. The member 240 is arranged in the groove 218, opening 221, pocket 220 and extends into the opening 222. Within the latter is 35 a spring controlled piston 249 of cup type and an abutment member 250 (Figure 3). The latter includes a head 251 mounted on the pivot 212 and has a rounded outer side. Extending from the inner side of head 251 towards the plunger 249 is a spring rest 252. Mounted in the piston 249 and extending therefrom to the inner side of head 251, as well as encompassing the rest 252, is a coiled controlling spring 253 which acts to normally extend the head 241 of locking member 240 40 to engage in groove 193 for locking element 211 stationary (Figure 3.) The plunger 249 bears against the inner rear end of stem 242. The structure 239 includes a releasing means 253^a for the locking member 240 and which is formed of 45 a pair of parallel spaced cams 254 and a shiftable latching arm 255 for the cams. These latter are mounted on pivot 256. The cams are arranged in pocket 220, straddle the stem 242, are disposed in and extend through the side 50 grooves of the stem 242. The cams 254 are in-

tegral with the upper face of the forward end of the latching arm 255. The latter has a curved upstanding flange 256^a at its rear end for frictionally engaging with the rear side of the head 251 to latch cams 254 in normal inactive position. When arm 255 is in frictional engagement with head 251, it is seated in groove 193 of part 214 of element 211. When arm 255 is released from head 251 and swung downwardly and forwardly, the cams 254 will be shifted to ride against the rear walls of the grooves in stem 242 whereby the latter will be shifted rearwardly against the action of spring 253 and move the locking head 241 from the groove 192 to release element 211. 5

The element 211 when locked also provides 15 means to lock the carrier 1 to prevent it from moving forwardly relative to the head of the stock structure 60, and in this connection, when element 211 is in its locked or elevated position, it has the edge portions 257 (Figure 21) which 20 constitute shoulders abut the oppositely inclined forward end edges 131 of the arms 136 of the element 127.

The portions of the side parts 17, 18 of the carrier 1 arranged forwardly of the breech block 25 element 94, when the latter is in rearward position, as shown in Figure 8, provide the loading chamber or space 258 of the gun. The chamber 258 extends forwardly with respect to the passage 234. When the cartridge 163 is fed to the 30 chamber 258 forwardly of element 94, the rear end of the cartridge 163 opposes an annular recess 259 formed in the leading end of element 94. As the latter moves forwardly, it receives the said rear end of the cartridge and moves the latter 35 forwardly into the firing chamber 164. When cartridge 163 is in position to be fired the forward end of shell 162 abuts shoulder 56 and the rear or flanged end 161 of the shell 162 is seated in recess 259. The forward face of the flange of 40 shell 162 when seated in recess 259 is flush with the forward face of element 94 and overlapped by the nose 160 of element 107. When the cartridge 163 is in position to be fired, the bevelled portion 57 of the wall of opening 41 retains the 45 shell extractor element 107 in the position as shown in Figure 9.

The shell 162 after the cartridge 163 has been fired is ejected upwardly from between the side parts 18, 19 as the breech block element 94 moves 50 rearwardly on recoil to the position shown in Figure 8.

The shell rejector 232 prevents the cartridge from moving rearwardly relative to element 214.

When using the gun initially, the loading and 55 firing is had manually, after which the loading and firing is had automatically.

Initial loading.—It will be assumed that the parts supported by the carrier 1 are in the position shown in Figure 5 and that the cartridge 60 feeding mechanism has been released for feeding cartridges from the magazine into the loading chamber, after which the grip 61 is moved rearwardly against the action of the spring controlled structure 59 whereby the rods 65 will be 65 moved rearwardly and which in turn, coacting with the pins, studs or abutments 99, will carry the element 94 rearwardly whereby the element 127 (Figure 8) will be moved downwardly on its pivot, but at the same time the latching member 116, due to the action of its controlling spring will be disposed horizontally and in a position to permit of the keeper 115 riding over and being positioned rearwardly of the sear or nose 141. As the element 94 moves rearwardly the loading 75

chamber or space 258 will be formed forwardly thereof and a cartridge 163 forced into the chamber or space 258. When element 94 moves rearwardly the springs 154 will be compressed, due to the necks 97 and heads 78 of the arms 96 forming parts of element 94. When hand grip 61 is released the spring 81 will move it forwardly and the springs 154 will act to shift element 94 forwardly to impact wall 10 of carrier 1, and at the same time the cartridge from the loading chamber will be forced into the firing chamber by element 94 on the forward movement of the latter. As element 94 moves forwardly, the keeper 115 of element 101 will engage the flat back of the sear or nose 141. The said engagement of keeper 115 and sear 141 will arrest the forward movement of element 101 to hold the latter in the position shown in Figure 9 thereby compressing the spring 117. The spring 117 is employed for initially firing the gun when keeper 115 is released.

For initial firing.—After the parts are in the position as shown in Figure 9, the trigger element 185 is manually moved rearwardly by the application of pressure thereto, which in turn, carries the element 204 rearwardly whereby lug 209 will contact with leg 236 of element 235, shift the latter rearwardly and move the sear or nose 141 clear of keeper 115, at which time spring 117 is released to provide for its acting to move element 101 forwardly to fire the cartridge.

Automatic firing.—During and after the initial firing of the gun, the manually applied pressure is continued on the trigger element 185, thereby providing for the maintaining of the element 235 in a position to hold the sear or nose 141 clear of keeper 115. The recoil from the initial firing will move the barrel, carrier 1 and element 94 in unison rearwardly to a slight extent and then move the element 94 rearwardly independently of the barrel and carrier 1. As element 94 moves rearwardly independently of the barrel and carrier 1, the loading chamber or space 258 will be formed forwardly thereof and into which a cartridge will be fed. After the initial firing, the element 101 will be at the forward portion of element 94 and held in such position by spring 117. As the element 94 moves rearwardly, the springs 154 will be compressed. At the limit of the recoil movement of the element 94, the springs 154 will become active causing the element 94 to quickly move forward whereby element 94 will shift the cartridge into the firing chamber and impact against the inner face of the wall 10 of the carrier. The force of the impact will be such as to create sufficient inertia to provide for the element 101 contacting with and exploding the cartridge in the firing chamber. The foregoing manner of automatic firing is carried out until the magazine is depleted of cartridges or until the applied pressure to the trigger element 185 has been removed. On the recoil of the element 94 after the initial and subsequent firings the shells of the cartridges are removed by the shell extractor element 107 which is bodily carried with element 94 and withdraws the shells from the firing chamber for discharge from carrier 1.

What I claim is:

1. In a sub-machine gun, a lock-block element including a depressible guided body part pivotally supported at its rear end and provided with a spring controlled latching member mounted in, pivoted to and extending forwardly from the forward end of said body part, said member being formed at its forward end with an upstanding

sear for releasably holding a cartridge firing means from action, and said body part having its sides provided with guides therefor.

2. In a sub-machine gun of that type including a shiftable firing element having a depending keeper, a lock-block element including a spring controlled sear adapted to engage the keeper to arrest movement of the firing element, the combination of a support, a spring controlled shiftable holding element including a skeleton body part 10 slidably mounted in said support, said holding element including a stem at the forward end and a lug at the rear end of said body part, said lug providing when said holding element is shifted in a rearward direction and held stationary after 15 being so shifted to maintain the sear clear of the keeper, and pressure applied means connected to said stem for shifting said element in said direction and for holding said element stationary.

3. In a sub-machine gun, a sear releasing 20 structure comprising a slidably mounted pusher element of skeleton form having a bifurcated stem at its forward end, a pressure applied trigger element formed with an oppositely grooved cap piece interengaging with and suspended from said 25 stem for shifting the pusher element rearwardly, and a spring controlled shiftable sear releasing element arranged in the rearward path of and shiftable by the rear end of the said pusher element in a direction to release the sear. 30

4. In a sub-machine gun, a sear releasing structure comprising a slidably mounted pusher element of skeleton form having a bifurcated stem at its forward end, a pressure applied pusher element formed with an oppositely grooved cap 35 piece interengaging with and suspended from said stem for shifting the pusher element rearwardly, and a spring controlled shiftable sear releasing element arranged in the rearward path of and shiftable by the rear end of the said pusher element in a direction to release the sear, said 40 releasing element being formed of a spring controlled horizontal leg arranged in the path of the rear end of said pusher element and a vertical leg extending upwardly from the forward end of the 45 horizontal leg and having its upper rear corner beveled.

5. In a sub-machine gun, a carrier, a reciprocating breech-block element mounted therein, a barrel anchored to the carrier, a lock-block element mounted in and slidably interengaging at the sides thereof with the carrier, a carriage slidably supporting the breech-block element, said lock-block element being pivoted at its rear end to said carriage and arranged rearwardly of and 50 depressed by said breech-block element on the movement of the latter in one direction, a stock structure including a head at its upper end for slidably supporting the carrier and a cartridge magazine communicating with the carrier 55 through said head, a firing element arranged within, bodily carried by and shiftable relative to said breech-block element, and a combined controlling, connecting and carrier structure arranged within and pivoted to the head, said 60 structures having coacting means for locking them together.

6. In a sub-machine gun, a trigger element including an upstanding curved arm having a flat top, a stem on said top and spaced from the sides 70 of the latter, and a cap piece carried by the stem and coacting with the latter and with said top to form a pair of oppositely opening grooves for receiving a pusher element.

7. In a sub-machine gun, a pusher element in- 75

- cluding a frame-like body part including a front and end wall, a pair of side walls and a rear end wall of less height than the other end wall, a bifurcated stem extending forwardly from said front end wall for interengaging with a trigger element and a lug on an edge of the rear end wall and arranged between and spaced from said side walls.
8. In a sub-machine gun, a pivoted combined controlling, connecting and carrier element including a body part formed intermediate its ends with a pocket having its mouth at the bottom of said body part, the latter being provided respectively with a groove in its forward end, an opening for establishing communication between said groove and pocket, a U-shaped recess in its front above said groove, a socket above said opening communicating with said recess and an elongated opening extending rearwardly from said pocket, said element including an inverted substantially U-shaped member extended forwardly from the top of said body part above said recess, and a pair of spaced parallel arms extended forwardly from the top of said member.
9. In a sub-machine gun, a pivoted combined controlling, connecting and carrier element including a body part formed intermediate its ends with a pocket having its mouth at the bottom of said body part, the latter being provided respectively with a groove in its forward end, an opening for establishing communication between said groove and pocket, a U-shaped recess in its front above said groove, a socket above said opening communicating with said recess and an elongated opening extending rearwardly from said pocket, said element including an inverted substantially U-shaped member extended forwardly from the top of said body part above said recess, a pair of spaced parallel arms extended forwardly from the top of said member, and a spring controlled locking structure mounted in said groove, openings and pocket and extended from the mouth of the pocket.
10. In a sub-machine gun, a pivoted combined controlling, connecting and carrier element including a body part formed intermediate its ends with a pocket having its mouth at the bottom of said body part, the latter being provided respectively with a groove in its forward end, an opening for establishing communication between said groove and pocket, a U-shaped recess in its front above said groove, a socket above said opening communicating with said recess and an elongated opening extending rearwardly from said pocket, said element including an inverted substantially U-shaped member extended forwardly from the top of said body part above said recess, a pair of spaced parallel arms extended forwardly from the top of said member, a spring controlled locking structure mounted in said groove, openings and pocket and extended from the mouth of the pocket, and a spring controlled sear releasing element mounted in said recess and socket and disposed below said member.
11. In a sub-machine gun, a horizontally disposed combined recoil and spring actuated reciprocating breech-block element formed with apertured arms at its forward end, a carrier in which said element is slidably disposed, said carrier including a front wall to be impacted by said element on its forward travel and being open at its rear end, a bridge piece slidably mounted in the rear end of the carrier, forwardly extending spaced parallel guide rods, one arranged at each side of said element, said rods connected at their rear ends connected to the bridge piece and extending through the arms of said element, and coiled springs mounted on said rods and interposed between said arms and bridge piece.
12. In a sub-machine gun, a horizontally disposed combined recoil and spring actuated reciprocating breech-block element formed with apertured arms at its forward end, a carrier in which said element is slidably disposed, said carrier including a front wall to be impacted by said element on its forward travel and being open at its rear end, a bridge piece slidably mounted in the rear end of the carrier, forwardly extending spaced parallel guide rods, one arranged at each side of said element, said rods connected at their rear ends connected to the bridge piece and extending through the arms of said element, coiled springs mounted on said rods and interposed between said arms and bridge piece, a barrel anchored to said carrier, said wall being formed with an opening for receiving the inner end of the barrel, said element when moving rearwardly providing for a portion of the carrier to form a loading chamber aligning with the inner end of the barrel for receiving a cartridge to be shifted into the barrel on the forward movement of said element, and an inertia operated firing element carried by the breech-block element.
13. In a sub-machine gun, a breech-block element, a carrier including a barrel receiving means, a stock including a head at its upper end, said head extending forwardly and rearwardly with respect to the upper end of said stock, said carrier extending above and being slidably connected to said head, and a combined controlling, connecting and carriage structure arranged within and pivotally connected to said head, said element being slidably mounted in said structure, said stock and structure having coacting means for locking the structure to the stock.
14. In a sub-machine gun, a horizontally disposed combined recoil and spring actuated reciprocating breech-block element formed with oppositely extending apertured lateral arms at its forward end, a carrier in which said element is slidably disposed, said carrier including a forward wall to be impacted upon by said element on the forward travel of the latter, said carrier being open at its rear end, a bridge piece slidably mounted in the rear end of the carrier, forwardly extending spaced parallel guide rods connected to the bridge piece, arranged at opposite sides of said element and extending through the arms, said arms being hollow at their forward end terminal portions, slotted lengthwise of said portions and open at their forward ends, coil springs mounted on said rods between said arms and bridge piece, means for initially loading the gun including shiftable parts extending into said portions and the slots of the latter and slidably connected to said rods, and coil springs within said portions rearwardly of said parts.

LOUIS NOLAN NOMAR.
